(57) **CLAIM**

The ornamental design for a shark shaped corkscrew, as shown and described.

DESCRIPTION

FIG. 1 is a front side elevation of a first embodiment of a shark shaped corkscrew embodying my new design, the rear side elevation view being a mirror image thereof;

FIG. 2 is a top plan view thereof;

FIG. 3 is a bottom plan view thereof;

FIG. 4 is a rear elevational view thereof;

FIG. 5 is a front elevation view thereof;

FIG. 6 is an expanded side elevation view of a second embodiment of the shark shaped corkscrew which has exactly the same appearance as the first embodiment except for the alternative screw feature; and,

FIG. 7 is a folded front side elevation view of FIG. 6.
